UNITED STATES PATENT OFFICE.

JOHN T. JONES, OF IRON MOUNTAIN, MICHIGAN.

ORE-REDUCING FURNACE.

No. 866,280.

Specification of Letters Patent.

Patented Sept. 17, 1907.

Application filed May 22, 1907. Serial No. 374,981.

To all whom it may concern:

Be it known that I, JOHN T. JONES, a citizen of the United States, residing at Iron Mountain, in the county of Dickinson and State of Michigan, have invented a new 5 and useful Improvement in Ore-Reducing Furnaces, of which the following is a specification.

The object of my invention is to provide a novel construction of furnace to adapt it to perform the work of the method of reducing ore which forms the subject 10 of my concurrent application for Letters Patent Serial No. 374,980, filed on the 22nd day of May, 1907.

The method referred to consists, generally stated, in recovering the iron, manganese, copper, and the like, in the form of pure metal, from the ore containing it 15 in reducible condition, by passing through a column of the ore in a finely divided condition and mixed with coke or other refractory material, in lump form, the hot products of combustion from carbonaceous fuel, preferably soft coal, to the exclusion of air and without 20 melting the ore, as is the practice in smelting furnaces, wherein coke, lime and silica are commonly mixed with the ore, with the result of contaminating the metal with impurities, which is avoided by my said method. Further steps involved in the aforesaid method relate 25 to distilling from the coal its contained hydrocarbons for admixture with the products of combustion from the coal on their way to the ore-stack, to augment the reducing action to which the ore is subjected; to promoting the combustion of the spent hot products for 30 utilizing the waste heat in preliminarily heating the ore in the upper part of the stack; to cooling the reduced product in a chamber from which air is excluded, and to crushing the ore thus treated to a fine mesh to free it from the gangue preparatory to separating it therefrom 35 by magnetic, gravity or other method of separation.

Referring to the accompanying drawing—Figure 1 shows my improved furnace by a view in sectional elevation; Fig. 2 is a section taken at the line 2 on Fig. 1 and viewed in the direction of the arrow, and Fig. 3 40 is a section like that presented by Fig. 2, but showing a modified construction of the furnace.

A stack 4 of suitable fire-brick construction rises, to a height of about one hundred feet, more or less, from the ground surface, at which it is provided, by preference, with a metal base 5. For this height of stack desirable dimensions for the walls are eighteen inches, and the same diameter for the interior. The stack, which contains a poker-hole 6 near its lower end and air-inlet ports 7 toward its upper end—say at a point 45 about seventy-five feet above the ground level—opens at its base into a close cooling-chamber 8 formed in a pit below the ground level, the height of which may be about twenty feet and the width about thirty inches. In the base of the cooling-chamber is indicated a rotary 50 conveyor 9 for carrying off the cooled ore after it has been subjected to the cooling-treatment. On one wall 55

of the stack is constructed a coal-burning furnace 10 extending from below the ground level to a height of about twenty-five feet, more or less, above the same, and containing a fuel-chamber 11, the preferred diameter of 60 which is about two feet. A grate 12 is provided in the lower part of the fuel-chamber, and below the grate is indicated a rotary conveyor 13 for removing the ashes, the firing being performed through an opening 14 in the furnace-wall, equipped with suitable removable 65 closing means. A poker-hole 15 is provided in the front wall of the furnace, which is fed at its upper end through a hopper 16 containing a bell-valve 17 for the usual purpose; and the furnace-chamber is expanded from its upper end for some distance downward to allow 70 for the swelling of the coal. About midway between the ends of the furnace 10 it communicates with the stack through a passage or flue 18, of the preferred shape represented.

As shown in Figs. 1 and 2 the structure is of rectangular shape in cross-section, the stack being sufficiently wide for providing it with four of the furnace-chambers 11, each having a flue-communication 18 with the stack and being otherwise equipped as described of the furnace-structure shown in Fig. 1. It will be understood, 75 however, that the structure may have one or more furnaces communicating with the stack. It is also feasible to construct the stack 4 in the cylindrical form represented in Fig. 3, when the furnaces 10 would be erected at right angles to each other about it, as shown in that 80 figure, the area of the interior of the stack being, of course, less when one furnace is provided and proportionately greater for each additional furnace.

To operate my improved furnace, the ore to be treated is introduced into the stack from its upper end thereby filling the stack and also the chamber 8, from which air is excluded. The fuel used in the furnace is preferably soft coal, the variety thereof best suiting my purpose containing about sixty per cent. carbon, about thirty per cent. of volatilizable hydrocarbons, and about ten per cent. ash. The coal is fed to the furnace-chamber through the hopper 16, filling that chamber, and is ignited through the opening 14, the fire being fed with air through a blast thereof admitted at a port 19 provided in a wall of the furnace-chamber below the 90 grate. The fuel in the chamber 11 becomes and is maintained incandescent above the level of the base of the passage 18, that portion of the bed which extends thence above that level being sufficiently heated from below to distil off its contained hydrocarbons, which 95 are volatilized by the heat and mix with the gases from the incandescent fuel in the flue 18, thereby greatly enriching the gases and augmenting their reducing action in the stack 4, into which they pass through the flue, rising therin through the ore in the stack. It is 100 found to be advantageous to mix with the body of the ore supplied to the stack, which is very coarse, of the 105

size of the fist, or thereabout, smaller or finer lumps of the ore to reduce the interstices in the column accordingly and the better diffuse through it the hot products of combustion which rise in the stack and by their action exerted upon the ore eventually reduce the oxygen constituent thereof and leave the pure metal. At about the point in the stack at which the ports 7 are provided the products of combustion become so far spent as to render it advantageous to mix air with them, 10 which is done through the said ports, with the result of promoting their combustion and adapting them to preliminarily heat the raw ore above that point, whereby the advantage of economy is secured in utilizing practically all the units of heat in the fuel and employing 15 what would otherwise be waste heat for partially or preliminarily acting upon the ore.

The ore introduced into the chamber 8 at the beginning of a run is removed therefrom by the conveyor 9 in its raw condition, to be again fed to the stack during the run. All the ore above the said chamber becomes reduced at the base thereof under the effect of the heat from the furnace or furnaces, whereby the metallic constituent of the ore is in the form of pure metal. In this last-named condition of the ore it descends into 25 the chamber 9, wherein it remains sufficiently long to cool it before exposure to air; and it is thus prepared for crushing to a sufficiently fine mesh to liberate the metal from the gangue preliminary to separating the metal, as hereinbefore stated.

30 What I claim as new and desire to secure by Letters Patent is—

1. In an ore-reducing furnace, the combination of an ore-stack, and a carbonaceous-fuel-burning furnace at the base of said stack having a flue-connection therewith leading from the furnace-chamber about midway between its upper and lower ends and adapted to conduct the gases from the incandescent fuel in the lower section of said

chamber and the volatilized hydrocarbons from the fuel in the upper part thereof into said stack and direct the products of combustion upwardly through the column of ore therein to discharge at the upper end of the stack, for the purpose set forth. 40

2. In an ore-reducing furnace, the combination of an ore-stack having air-inlet ports in the upper part of its wall, and a carbonaceous-fuel-burning furnace at the base of said stack having a flue-connection therewith leading from the furnace-chamber about midway between its upper and lower ends and adapted to conduct the gases from the incandescent fuel in the lower section of said chamber and the volatilized hydrocarbons from the fuel in the upper part thereof into said stack and direct the products of combustion upwardly through the column of ore therein to discharge at the upper end of the stack, for the purpose set forth. 45 50

3. In an ore-reducing furnace, the combination of an ore-stack rising from a base, a pit below said base forming a close cooling-chamber into which the stack discharges and equipped with means for removing the reduced ore, a furnace exterior of the stack, having about midway between its upper and lower ends a passage for the products of combustion into the stack, a coal-burning grate in the lower part of the furnace-chamber and an air-blast port in the wall of the furnace below the grate, for the purpose set forth. 55 60

4. An ore-reducing furnace comprising, in combination, an ore-stack rising from a base and provided in the upper portion of its wall with air-inlet ports, a pit below said base forming a close cooling-chamber into which the stack discharges and equipped with means for removing the reduced ore, and a furnace exterior of the stack near its base and communicating therewith from between its ends through a flue leading into the stack near its base, said furnace having a valve-closed feed-hopper on its upper end and containing a coal-burning grate in its lower portion and an air-blast port below the grate, for the purpose set forth. 65 70 75
